UNITED STATES PATENT OFFICE.

CHARLES WHITING BAKER, OF MONTCLAIR, AND JOHN J. SWAN, OF PLAINFIELD, NEW JERSEY.

APPARATUS FOR FEEDING FUEL TO OIL-ENGINES.

1,149,323.

Specification of Letters Patent. Patented Aug. 10, 1915.

Application filed December 11, 1913. Serial No. 805,932.

To all whom it may concern:

Be it known that we, CHARLES WHITING BAKER, of Montclair, county of Essex, and State of New Jersey, and JOHN J. SWAN, of Plainfield, county of Union, and State of New Jersey, have invented certain new and useful Improvements in Apparatus for Feeding Fuel to Oil-Engines, of which the following is a specification.

10 Our improvements relate to a system of fuel feeding, such as is described in United States application Serial No. 782,158, filed by said Charles Whiting Baker July 31, 1913, in which the liquid fuel is fed to the engine continuously by a pump and is atomized by a current of gas moving at high velocity, and our improvements relate to means for driving the fuel feeding pump and for producing the current of gas for 20 atomizing the fuel with means for heating the atomized fuel.

Our improved fuel feeding apparatus is illustrated in the accompanying drawings in which—

25 Figure 1 is a vertical section through the apparatus which is attached to the air inlet pipe of the engine; Fig. 2 a vertical section at right angles to Fig. 1; Fig. 3 a partial front view of the gear pump with the cover removed; Fig. 4 a section of a form of our apparatus adapted for use with non-volatile fuels such as kerosene; and Fig. 5 a vertical section at right angles to the section in Fig. 4.

30 Our method of feeding fuel to oil engines here described consists essentially in drawing the air supply for the engine through an air motor which is rotated at a speed proportionate to the amount of air passing to the engine, and utilizing the power of the 35 air motor, through speed reducing gearing, to drive a small pump which has its suction pipe connected to a reservoir of liquid fuel and its delivery pipe discharging into an atomizing passage through which a current 40 of air or gas is caused to flow at high speed, delivering the atomized fuel into the engine intake pipe.

45 Referring to the drawings the numeral 1 designates the air motor, consisting of the 50 circular case 2, in which revolves the wheel 3, having vanes 4, against which the air entering through the tangential intake tube 5 impinges. The air passes out through the tangential delivery tube 6 which is connected to the intake pipe of the engine. The

wheel 3, being thus driven by the air entering the engine, imparts motion to the rotary gear pump by means of the pinion 7, driving the gear wheel 8 on the intermediate shaft 9, which in turn drives the gear wheel 10 secured to the driving shaft of the pump 11, through gear 12.

55 The suction pipe 13 of the pump (see Fig. 4) is connected to a source of liquid fuel, and the delivery pipe 14 is led to the atomizing tube 15 which is placed in the center of the delivery tube 6. The current of air passing at high velocity through tube 6 induces a current through the atomizing passage 15. In order that air may flow at 60 high velocity through the atomizing passage 15, even when the engine is running slowly and consuming a small volume of air, we place a pair of shutters 17 and 17' in the delivery tube 6, hinged to the sides thereof and 65 meeting at the center, their edges being so formed as to close around the atomizing tube. Springs 18 and 18' are so arranged as to turn the shutters toward the center. When the shutters are closed against the 70 atomizing tube 15 all the air passing to the engine has to pass through this small tube. As the speed and air consumption of the engine increases, the suction of the entering air will exert a force tending to open the 75 shutters greater than the force of the springs which tend to close them, and the shutters will open wider and wider with increasing speed. The springs 18 and 18' are so proportioned that the force tending to turn the 80 shutter is nearly the same at all points of the shutter's motion. The springs may be set, for example, so that at a suction of 1 oz. per sq. in., the shutters will begin to open 85 and allow part of the inrushing air to pass up on the outside of the atomizing tube. High velocity will still be maintained through the atomizing tube, however, as its flaring open end is impinged upon by a column of air moving at great velocity, and a 90 suction is also produced on its upper end by the friction of the moving air column.

95 In order that the liquid fuel may be evenly distributed around the periphery of the atomizing passage, small spiral vanes 19 are 100 placed at the entrance of the atomizing tube 15 to give the atomizing air current a whirling motion. It will be noted that any liquid fuel which may not be perfectly atomized 105 and may drop back down the delivery tube, 110

will be again thrown up the tube at high velocity by the rapidly rotating vanes of the air motor. The case of the air motor being made tight against leakage, loss of liquid fuel is rendered impossible. Instead of using an air current produced by the engine itself to effect atomization, in the manner shown in Figs. 1 and 2, we may use a current of hot gas taken from the engine cylinders in the manner described in said Baker's application Serial No. 782,158, filed July 31, 1913, and we prefer to do this where kerosene or similar fuels volatile only at relatively high temperatures are to be used.

In such cases also we prefer to submit the mixture of atomized fuel and hot gas to the action of heat before discharging it into the air intake in the manner illustrated in Figs. 4 and 5. Referring to these figures, the atomizing tube 15, is here placed on the exterior of the air inlet passage. The current of gas used to atomize the liquid fuel delivered from the pump through the pipe 14, is here provided by a pipe 20 leading from the engine cylinders, in the manner shown in said Baker's application Serial No. 782,158 above referred to. The hot gas, with its load of atomized fuel, passes at high velocity through the coiled pipe 21, and finally emerges as a jet of mingled gas and fuel from the nozzle 22 in the center of the air intake pipe 23. In order to heat the coil 21, it is surrounded by a casing 24, covered with heat insulating material 25 and hot exhaust gas is drawn from the exhaust pipe of the engine through the pipe 26, and is discharged from the casing through the pipe 27, which is led back to the exhaust pipe again.

In constructing the above described apparatus, the proportion of the air to the fuel delivered will be fixed by the relative capacities of the air motor and the fuel pump and the ratio of the speed reducing gearing by which the former drives the latter. It is, however, of advantage to place the proportion of air to fuel under control of the engine driver, so that he can vary the power of the engine not only by the throttle valve in the inlet air pipe but by varying the richness of the mixture. It is also desirable that the air motor shall run even when very small amounts of air are passing through it, as when the engine is running very slowly.

As the circumferential velocity of the air motor varies with the velocity of the impinging air current entering the intake tube 5, we place a swinging valve or shutter 28 in the intake tube 5. This shutter, by its own weight, swings into the position shown by the dotted line 29, in which position the intake tube is nearly closed, leaving only a narrow opening on the outer side. When the shutter is in this nearly closed position, the air entering the narrow slit, left open,

has to pass at much higher velocity than if the shutter were wide open and it strikes the moving vanes 4 close to their ends where its force causes the greatest turning moment. As soon as the speed of the engine increases so that a greater volume of air is drawn through the motor, the shutter 28 is automatically opened wider by the suction. The amount of opening of the shutter is limited by the movable stop 30, adjusted by a swinging arm 31, and a connection 32 from this arm to a lever conveniently located enables the engine driver to instantly adjust the stop 30, so as to give the desired proportion of air to the fuel. In order that the speed reducing gearing and the air motor may be continuously lubricated without frequent attention, we inclose the gearing between the motor and the pump in a casing 33 the lower part of which may be filled with oil in which the gear wheel 8 will dip as it revolves. The wheel 3, of the air motor may turn in ball bearings which may be lubricated from the gear casing.

The pump 11 driven by the air motor may be of any suitable form but we prefer to use a rotary gear pump consisting of a pair of intermeshing gear wheels revolving in a closely fitting case, the shaft of one of said wheels being driven by the air motor as already explained.

Very accurate fitting of the gear wheels to the case is desirable, so that the pump may operate with a low percentage of slip and yet may turn freely with little friction. In the delivery pipe from the pump 11 to the atomizing tube 15 we place a loaded check-valve 34. This valve prevents any leakage through the pump to the atomizing nozzle except when the pump is running and delivering fuel under pressure sufficient to lift the check-valve from its seat. It also makes the head against which the pump works practically constant at all speeds.

What we claim and desire to secure by Letters Patent of the United States is:—

1. In a fuel feeding system for oil engines, the combination of a motor driven by the entering air current, a liquid fuel pump driven by said motor, means for producing a rapid current of air or gas through a passage into which the liquid fuel from said pump is delivered, means for delivering said current charged with liquid fuel into the engine intake, and means for varying the speed of the air motor for a given rate of air consumption by the engine.

2. In a fuel feeding system for oil engines, the combination with a motor driven by the entering air current and a pump driven by said motor, of means for varying the speed of the air motor for a given rate of air consumption by the engine.

3. In a fuel feeding system for oil engines, an air intake, a motor mounted in said in-

take and adapted to be actuated by the entering air current, a fuel pump connected to and actuated by said motor, a pipe for delivering the fuel to the intake, and means

5 for varying the speed of the air motor for a given rate of air consumption by the engine.

4. In a fuel feeding system for oil engines, an air intake, a motor mounted in said intake and adapted to be actuated by the entering air current, a fuel pump connected to and actuated by said motor, an atomizer in the intake, a pipe to deliver the fuel to said atomizer, and means for varying the speed of the air motor for a given rate of air con- 10 sumption by the engine.

5. In a fuel feeding system for oil engines, an air intake, a motor mounted in said intake and adapted to be actuated by the entering air current, a fuel pump connected to and actuated by said motor, an atomizer in 15 the intake on the delivery side of the motor,

a pipe to deliver the fuel to said atomizer, and means for varying the speed of the air motor for a given rate of air consumption by the engine.

25

6. In a fuel feeding system for oil engines, an air intake, a motor mounted in said intake, and adapted to be actuated by the entering air current, a liquid fuel pump driven by said motor, and a valve in the in- 30 take on the entering side of said motor controlling the inflow of air to the motor and adapted to vary its speed.

In witness whereof we have hereunto signed our names in the presence of two sub- 35 scribing witnesses.

CHARLES WHITING BAKER.
JOHN J. SWAN.
